OSCILLOGRAPH

William H. Mayne, San Antonio, Tex., assignor to
Olive S. Petty, San Antonio, Tex.

Application June 24, 1941, Serial No. 399,549

6 Claims. (Cl. 171—95)

This invention relates to improvements in oscillographs, especially instruments of the multiple string type. It is the primary object of the invention to minimize distortion of the record produced by such instruments as the result of undesirable string vibrations.

More specifically, it is an object of the invention to confine the strings to movement in prescribed paths such as will ensure freedom from tangling or collision and to control string displacement by adequate and effective damping.

The invention is illustrated as applicable to a multiple string galvanometer of the Einthoven type in which a plurality of strings are supported in parallel relation in a magnetic field, and in which a beam of light, projected on a moving sensitized sheet, is intercepted by the strings so that string vibration resulting from varying flow of current in the strings may be recorded. It is customary in such instruments to concentrate the magnetic field adjacent the strings by the use of pole pieces, and it is desirable to incline the faces of the pole pieces at an acute angle with respect to the plane of the strings, so that the strings will not tangle or collide even though disposed in closely contiguous relation. It is a feature of the invention that these pole pieces are offset in the direction of a normal to the strings lying in the plane of the strings, in order that the end strings of the series will not collide with or tangle with the ends of the pole pieces when vibrating in planes normal to the magnetic field.

It is a further object of the invention to control the vibration of the strings by the provision of effective electrical damping. To this end, the resistance of the circuit containing the string is minimized by the provision of a suitable shunt for the usual tensioning spring, and the pole pieces are so dimensioned with respect to the length of the string, and the light beam so projected across the spring, as to minimize distortion resulting from modes of vibration other than the fundamental.

Further objects and features of the invention will be apparent from the following description taken in connection with the accompanying drawing, in which:

Figure 1 is an end elevation of the essential elements of an oscillograph constructed in accordance with the instant invention;

Figure 2 is a view taken substantially on the line 2—2 of Figure 1;

Figure 3 is an enlarged view of the string 55

tensioning spring and associated shunt shown in Figure 1;

Figure 4 is an enlarged sectional view of the pole pieces shown in Figures 1 and 2;

5 Figure 5 is a diagrammatic view similar to Figure 4 and illustrating the disposition of the magnetic lines of force between the pole pieces; and

Figure 6 is a view corresponding to Figure 5, 10 illustrating the magnetic lines of force when the pole pieces are not offset.

In order to facilitate an understanding of the invention, reference will be made to the several embodiments thereof illustrated in the accompanying drawing and specific language will be employed. It will nevertheless be understood that various further modifications of the devices illustrated herein, such as would fall within the province of those skilled in the art to construct, 15 are contemplated as part of the present invention.

Referring first to Figure 1, it will be observed that the oscillograph strings 10 are illustrated as mounted in a supporting frame 11. Each 25 string is suitably tensioned by elastic means in the form of a coil spring 12 which is mounted at one end in the supporting frame 11 and is secured at its other end to the string. The strings 10 and the springs 12 are preferably separately insulated from the support 11 in order that they may be included in separate circuits for the recording of separately derived signal 30 energy. Shunting each spring 12 is a looped wire or other element suitably shaped to avoid interference with the motion of the string, the wire being formed of material of high conductivity, for example copper. By this means the resistance in the string circuit, ordinarily substantially increased by the spring which is commonly 35 made of phosphor bronze, may be reduced to a minimum in order to increase the electrical damping of the string.

For example, in a typical case, the resistance of the string and of the spring may be five ohms each, making a total resistance without the shunt connection of ten ohms. Thus 50% of the exciting energy is wasted in the spring. In order to obtain results which at least approach satisfactory efficiency with the ten ohm string and spring combination, the resistance of the external circuit should be at least thirty ohms. This means that the total D. C. resistance in the damping circuit will be forty ohms. However, if the shunt connection across the spring is employed so as to give an effective D. C. resistance

of five ohms in the string and shunted spring, the resistance of the external shunt can be reduced to fifteen ohms to afford the same efficiency, so that the total resistance in the damping circuit of the galvanometer is reduced from forty ohms to twenty ohms, with resultant doubling of the sensitivity as well as the damping.

The magnetic field for the strings is preferably provided by an electromagnet comprising a core 20 having energizing windings 21 associated therewith. The field is concentrated in the neighborhood of the strings by means of pole pieces 25 which may be bolted to the core as at 26. The strings 10 are arranged in parallel relation in a common plane, and the faces 28 of the pole pieces define parallel planes which are inclined at an acute angle with respect to the plane of the strings. This is desirable, as has been heretofore recognized, since the individual strings are thereby caused to vibrate in planes substantially parallel to the pole faces and may thus be arranged much more closely without risk of collision or tangling, with consequent increase in compactness and reduction in cost of the optical system associated with the instrument.

The sides of the pole pieces are tapered in the direction of the strings; in the embodiment of the invention shown, the inclination of the two sides of each pole piece to the base thereof is of the order of 72° and 65° respectively. It has been found that if this taper is too great the magnetic flux leakage is excessive, whereas if the taper is too slight, the magnetic flux is reduced by the resultant decrease in area of the pole pieces. The taper is accordingly selected so as to afford minimum leakage and maximum flux, having due regard to other factors, such as the permeability of the metal of the pole pieces at various flux densities, and the size of the gap between the pole pieces.

As is apparent from Figures 2, 4, and 5, the pole pieces are offset in the direction of a normal to the strings lying in the plane of the strings, this feature being important to avoid tangling of the end strings with the pole pieces on the occurrence of vibrations of large amplitude. Thus it will be noted from Figure 5 that by offsetting the pole pieces to a sufficient extent, the lines of magnetic force may be so directed that all of the strings vibrate in substantially parallel planes. If it were not for this offset, the condition illustrated in Figure 6 would obtain, and it will be appreciated that since the strings tend to move at right angles to the lines of force, and the lines adjacent the ends of the pole pieces are decidedly curved, the outermost strings will tend to move toward and around the adjacent pole piece ends.

In this connection it will be observed that by reason of the inclination of the pole pieces, that end of each pole piece which is closest to the strings presents the more acute angle between the pole face and the side of the pole piece, and the pole pieces are therefore offset in such a direction that these more acutely angled ends project further beyond the strings than do the less acutely angled ends.

I have found that it is important in preventing distortion of the record as the result of harmonic vibrations that the depth of the pole faces, as measured in the direction of the string length, should bear a ratio to the string length of the order of 5:9. This ratio is found to give the optimum results in the damping of vibrations of the first and third orders, resulting in adequate

damping for the fundamental, while not materially reducing the damping of the third harmonic of the string. The effect of second harmonic vibrations are eliminated by so positioning the string that the effective center thereof intercepts the light beam.

The optical means for producing the light beam is not shown herein but may assume any conventional form. The light is projected through bores 32 in the bases of the pole pieces and through slots 33 formed in the pole faces and extending into the pole pieces for a depth sufficient to provide uniformity of the magnetic field for the several strings.

It will be appreciated that while the invention is especially applicable to instruments of the multiple string type, certain features thereof are useful in connection with instruments having only one string. Instruments of this character are widely used in the field of seismic surveying in which impulses are simultaneously received at a plurality of points, and converted into electrical energy, the electrical waves being then impressed upon the separate strings of the oscilloscope to afford a series of traces on a single sensitized sheet representative of the seismic impulses arriving concurrently at the several points.

Having thus described the invention, what is claimed as new and desired to be secured by Letters Patent, is:

1. In an oscilloscope, the combination with a plurality of parallel oscilloscope strings defining a common plane, of means establishing a magnetic field transversely of the strings, said means including opposed pole pieces having parallel faces disposed at an acute angle to the plane of the strings, said pole faces being offset in the direction of a normal to said strings lying in said plane.

2. In an oscilloscope, the combination with a plurality of parallel oscilloscope strings defining a common plane, of means establishing a magnetic field transversely of the strings, said means including opposed pole pieces having parallel faces disposed at an acute angle to the plane of the strings, the angle formed by each pole face with that side of the pole piece which is closest to the plane of the strings being the more acute, said pole faces being offset in the direction of a normal to said strings lying in said plane, the more acutely angled sides of the respective pole pieces being disposed further beyond the strings.

3. In an oscilloscope, the combination with a plurality of parallel oscilloscope strings defining a common plane, of means establishing a magnetic field transversely of the strings, said means including opposed pole pieces having parallel faces disposed at an acute angle to the plane of the strings, said pole faces being offset in the direction of a normal to said strings lying in said plane, said pole faces having a depth, measured in the direction of the string length, such that the ratio of the depth to the string length is of the order of 5:9.

4. In an oscilloscope, the combination with a plurality of parallel oscilloscope strings defining a common plane, of means establishing a magnetic field transversely of the strings, said means including opposed pole pieces having parallel faces disposed at an acute angle to the plane of the strings, said pole faces being offset in the direction of a normal to said strings lying in said plane, a support for said strings, spring means connecting each of said strings to said support

to tension the strings, and means of high conductivity arranged in shunt with each of said springs to reduce the electrical resistance of the string circuit.

5. In an oscillograph, the combination with a plurality of parallel oscillograph strings defining a common plane, of means establishing a magnetic field transversely of the strings, said means including opposed pole pieces having parallel faces, said pole faces having a depth, measured in the direction of the string length, such that the ratio of the depth to the string length is of the order of 5:9.

6. In an oscillograph, the combination with a plurality of parallel oscillograph strings defining a common plane, of means establishing a magnetic field transversely of the strings, said means including opposed pole pieces having parallel faces, said pole faces having a depth, measured in the direction of the string length, such that the ratio of the depth to the string length is of the order of 5:9, and means projecting a light beam transversely of the plane of the strings and substantially at the mid-point of the string length.

WILLIAM H. MAYNE.
